UNITED STATES PATENT OFFICE.

JOHN J. JACOBS, OF NEW YORK, N. Y.

ELASTIC LINK.

1,280,744.

Specification of Letters Patent.

Patented Oct. 8, 1918.

Application filed June 3, 1916, Serial No. 101,470. Renewed August 1, 1918. Serial No. 247,871.

To all whom it may concern:

Be it known that I, JOHN J. JACOBS, a citizen of the United States, and a resident of the city of New York, borough of Manhattan, in the county and State of New York, have invented a new and Improved Elastic Link, of which the following is a full, clear, and exact description.

The invention relates to elastic links such as shown and described in the Letters Patent of the United States, No. 926,655, granted to me June 29, 1909.

The object of the present invention is to provide a new and improved elastic link more especially designed for use on belts, suspenders and like articles, and which is simple and durable in construction, cheap to manufacture and composed of comparatively few parts not liable to get easily out of order.

In order to accomplish the desired result, use is made of a U-shaped frame provided with guideways in its parallel arms, the latter having apertures near the free ends of the attaching bar closing the open end of the frame and having lugs engaging the said apertures to hold the attaching member in place on the parallel arms, a spring seated on the closed end of the said frame and guided in the said guideways, and a loop straddling the free end of the spring and the closed end of the said frame.

A practical embodiment of the invention is represented in the accompanying drawings forming a part of this specification, in which similar characters of reference indicate corresponding parts in all the views.

Figure 1 is a perspective view of a belt provided with the elastic link;

Fig. 2 is an enlarged side elevation of the same with parts broken out;

Fig. 3 is a transverse section of the same on the line 3—3 of Fig. 2;

Fig. 4 is a perspective view of the frame, the loop and the attaching member in disassembled position; and

Figs. 5, 6 and 7 are face views of modified forms of the frame and attaching member.

As illustrated in Figs. 1, 2 and 3, the elastic link 10 connects the belt band 11 with the buckle 12 adapted to be engaged by the free end 13 of the belt band in the usual manner. The elastic link 10 is provided with a U-shaped frame 14 having parallel arms 15, 16, connected with each other at one end 55 by an integral crossbar 17, and the arms 15,

16 as well as the bar 17 are U-shaped in cross section. A coil spring 18 has one end seated in the channel of the crossbar 17 while the ends of the convolutions of the spring 18 slidably engage the channels in the parallel arms 15 and 16, which latter thus form guideways for the spring 18 while the crossbar 17 is the seat for the spring. The free ends of the parallel arms 15 and 16 are provided with apertures 19, and into the said free ends of the channels of the guide arms 15 and 16 fits the attaching member 20 provided with lugs 21 extending through the apertures 19 thus securing the attaching member 20 in position on the free end of the frame 14 thereby closing the open end of the said frame. The attaching member 20 is provided with spaced bearings 22 for engagement by the bar 23 of the buckle 12 to allow the latter to swing on the attaching member 20. The free end of the spring 18 is straddled by a loop 25, preferably made of a piece of sheet metal doubled up, as plainly shown in the upper portion of Fig. 4, to overlie the spring 18 and straddle the connecting bar 17 of the frame 14, the loop 25 being of a width corresponding approximately to the distance between the arms 15 and 16, so that the spring is completely concealed in the frame 14 by the loop 25. The free ends of the loop 25 are provided with registering keyhole slots 26 adapted to be engaged by a double button 27 held on the band 11, which latter extends between the members of the loop 25, as plainly indicated in Fig. 3. By the arrangement described, the link can be readily attached at one end to the buckle 12 and at the other end to the band 11.

In practice, the attaching member 20 is preferably made from a single piece of sheet metal stamped out to the desired shape and doubled up so as to provide bearings 22, as will be readily understood by reference to Fig. 4. The attaching member 20 may, however, be provided with various means for attachment to another part of the article on which it is to be used; for instance, as shown in Fig. 5, the attaching member 20 is provided with a keyhole slot 30 for engagement with a stud similar to the stud 27, and, as shown in Fig. 6, the attaching member 20 is in the form of a buckle frame having a crossbar 40 and teeth 41 for retaining a strap or similar article on which the link is to be used. In the form shown in 110

Fig. 7, the attaching member 20 is in the form of a plain bar having apertures 50 for the passage of stitches to secure the attaching member to the part on which the link 5 is to be used.

On the link 10 are mounted loops 60 and 70, preferably made of leather, for receiving the end 13 of the band 11 after the said end has been engaged with the buckle 12. The 10 loop 60 extends around the link at the lugs 21 which project sufficiently beyond the arms 15 and 16 of the frame 14 to engage the inner surface of the loop 60 and thus to hold the same in position on the end of the link 15 adjacent the buckle 12. The other loop 70 is provided with a tongue 71 engaged with the tongue 72 of the buckle 12 to hold the loop in position on the link adjacent the band 11. Thus the loops 60 and 70 are always 20 held the desired distance apart for enhancing the appearance of the belt and for securely holding the free end of the band 11 in position.

From the foregoing it will be seen that 25 the several parts of the link can be readily assembled and attached to the parts on which the elastic link is to be used.

Having thus described my invention, I 30 claim as new and desire to secure by Letters Patent:—

1. In an elastic link, the combination of a U-shaped frame provided with guideways in its parallel arms, the latter having apertures near the free ends, a crossbar closing 35 the open end of the frame and having lugs engaging the said apertures to hold the crossbar in place on the parallel arms, a spring seated on the closed end of the said frame and guided in the said guideways, 40 and a loop straddling the free end of the spring and the closed end of the said frame.

2. In an elastic link, the combination of a U-shaped frame provided with guideways in its parallel arms, the latter having apertures near the free ends, a crossbar closing 45 the open end of the frame and having lugs engaging the said apertures to hold the crossbar in place on the parallel arms, a spring seated on the closed end of the said frame and guided in the said guideways, and a loop 50 straddling the free end of the spring and the closed end of the said frame, the free ends of the said loop having registering

keyhole slots, and a stud engaging the said slots.

3. In an elastic link, a frame provided 55 with parallel arms having guideways, and a connecting bar integrally connecting the said guide arms with each other at one end, the said guide arms having apertures near the free ends, and an attaching member fitting into the guideways and provided with outwardly projecting lugs engaging the said apertures.

4. In an elastic link, a frame provided 60 with parallel arms and an integral connecting member connecting the parallel arms with each other at one end, the arms and connecting member being each U-shaped in cross section to form guideways in the arms 70 and a seat at the connecting member, the said arms being provided with apertures at their free ends, and an attaching member having its ends fitting into the outer ends of the said guideways, the ends of the attaching member having outwardly projecting lugs 75 passing through the said apertures to hold the attaching member in place at the open outer end of the frame.

5. In an elastic link, a frame provided 80 with parallel arms and an integral connecting member connecting the parallel arms with each other at one end, the arms and connecting member being each U-shaped in cross section to form guideways in the arms 85 and a seat at the connecting member, the said arms being provided with apertures at their free ends, an attaching member having its ends fitting into the outer ends of the said guideways, the ends of the attaching 90 member having outwardly projecting lugs passing through the said apertures to hold the attaching member in place at the open outer end of the frame, the said attaching member having means for attaching it to a 95 part of the article on which the link is to be used, a coil spring seated in the said seat and having the ends of its convolutions guided in the said guideways, and a loop 100 passing around the free end of the spring and straddling the connecting member of the said frame, the said loop having at its ends registering keyhole slots and a stud on another part of the article and engaging the said keyhole slots.

JOHN J. JACOBS.
